OF CLEVELAND, OHIO, A CORPORATION OF OHIO

REFRIGERATION APPARATUS

Application filed December 27, 1927. Serial No. 242,574.

This invention relates to improvements in refrigeration apparatus of the intermittent absorption type.

Apparatus of this type consists, generally, 5 of a closed system incorporating a generator-absorber; an evaporator-receiver; a delivery conduit leading from the generator absorber to the evaporator-receiver, said conduit usually involving a condenser and, preferably 10 a dehydrator in advance of the condenser; a return conduit leading from the evaporator above the maximum liquid level therein to the generator-absorber below the minimum liquid level therein, together with 15 means for intermittently heating the generator-absorber.

The system permanently contains a quantity of a suitable refrigerant and an absorbent for the refrigerant. For the purpose of the 20 present disclosure this may be considered as the usual solution of water as the absorber and ammonia as the refrigerant, in proper proportions, but without any intention of limiting the present invention to the use of 25 these specific ingredients. Where the terms are used in the specification and claims they are to be understood as embracing any and all equivalents known to the art.

At the beginning of a cycle of operation 30 substantially the whole amount of solution is present in the generator-absorber. By heating the generator-absorber for a given period of time, the ammonia is driven out of solution and passes therefrom in the form of 35 vapor into the delivery conduit on its way to the evaporator-receiver, being dehydrated and condensed in the respective appropriate- 40 ly designated parts of said conduit, arriving in the evaporator-receiver in the form of liquid anhydrous ammonia. This phase of the operation is what is known as the heating period, and during this period a relatively high pressure prevails throughout the system which contributes to the condensation 45 of the ammonia in the cooler parts of the system, as in the condenser, from which the liquefied refrigerant flows to the evaporator-receiver where it is stored awaiting the evaporation period. As used hereinafter, the term 50 "evaporator", in certain instances, may or

may not embrace the receiver the intent will be clear from the context.

As soon as the heat is removed from the generator-absorber, what is known as the cooling period begins, and during this period, 55 a reversal of the foregoing conditions is effected. The weak liquor in the generator-absorber, by reason of its affinity for the ammonia, starts to absorb the ammonia gas that is drawn through the return conduit from 60 the evaporator, and as a consequence of this the pressure in the system falls. Incident to this fall in pressure, the liquid ammonia begins to boil, being vaporized by the heat abstracted from the relatively warm air surrounding the evaporator, thus cooling said 65 air for refrigeration purposes. In this prior practice suitable means, such as valves, traps, etc. is employed for preventing the ammonia gas from returning to the generator-absorber 70 by way of the delivery conduit and condenser and said gas is thus compelled to pass through the return conduit. All this will be recognized by those acquainted with the subject as being common to apparatus of the type 75 in question.

In refrigeration apparatus of the class described, unless some means is employed for overcoming the difficulty, the efficiency of the apparatus is greatly impaired, or virtually 80 destroyed, by an accumulation in the evaporator of a quantity of the aqueous contents of the system, the quantity gradually increasing with each cycle of operation until the effectiveness of the apparatus becomes prac- 85 tically nil.

It is the primary purpose of my invention to provide refrigeration apparatus of the type in question incorporating thoroughly reliable means that is positive of action and 90 immune from disorder for automatically returning to the generator-absorber during each heating period, all residue liquid that may have been left in the evaporator end of the system at the conclusion of the previous 95 cooling period. To the attainment of this end I employ a liquid return means or siphon that acts during the early stages of the heating period, as will hereinafter more fully appear.

A further and very important object of the invention is to provide, in apparatus of the class described, a unique, simple and highly efficient means, devoid of valves and moving parts, for causing the ammonia vapor to return from the evaporator to the generator-absorber without any substantial part of it passing through the condenser, and for assisting in the rapid absorption of the ammonia vapor in the water; and, more specifically, to provide a liquid seal for accomplishing this result that involves the liquid anhydrous ammonia that is in the evaporator.

Heretofore attempts have been made to use the highly volatile liquid anhydrous ammonia as a seal to prevent the return of the ammonia vapors through the condenser, but these attempts have failed because the tubes or conduits which it was desired to seal had invariably been exposed in the region of the seal to the relatively high temperature of surrounding air, thereby causing the ammonia to boil and thus, to a very considerable extent at least, defeating the object of the seal.

In my improved form of apparatus I am enabled to use liquid anhydrous ammonia as a seal because the tube which it is desired to seal, or a material part of it from its sealed end, is located inside the evaporator and the evaporation of the surrounding ammonia tends to keep it cool. To minimize the height of the liquid level in said tube necessary to effect said liquid seal, I use a very shallow submergence of the return conduit in the liquid in the generator-absorber, it being evident that these analogous conditions existing at the opposite ends of the system balance each other. By reason of this arrangement I am enabled to accomplish this result without having to resort to traps and valves.

Other and more general objects of the invention are to provide a highly efficient refrigeration apparatus of the above mentioned type that is simple of construction and involves no mechanically operating parts or valves; that is relatively inexpensive; that requires a minimum of attention; that is at all times in readiness for use and does not have to be manipulated in any way, as for the purpose of collecting its contents in a given part of the system, as in the generator-absorber (should the normal conditions of the apparatus have been disturbed through handling or shipping), preparatory to firing, the apparatus automatically reconditioning itself upon the initiation of each cycle of operation; to provide apparatus of the type referred to that is so constructed and arranged as to operate in cycles of given duration—as, for example, 24 hour periods, and which is fired by oil burning apparatus involving a reservoir or font of a capacity to accommodate just enough fuel to generate the heat required to initiate one cycle of operation.

Various embodiments of the invention by which the foregoing objects, with others hereinafter appearing, are attained, are illustrated more or less diagrammatically in the accompanying drawings, wherein Fig. 1 represents a sectional elevation of a refrigeration apparatus constructed in accordance with one form of the invention; Figs. 2, 3 and 4 are similar fragmentary views showing modifications, while Fig. 5 is a graph or chart on which is plotted curves representing the pressure and temperatures prevailing during a cycle of operation.

Referring by like numerals to the parts common to the various illustrative embodiments of the invention herein disclosed, 1 designates a generator-absorber, 2 an evaporator which serves also as a receiver for the refrigerant condensate, 3 a delivery conduit that leads from the generator-absorber to the evaporator, and 4 a return conduit by which the ammonia gas is conducted from the evaporator to the generator-absorber. Respective parts of the delivery conduit 3 constitute a dehydrator 5 and a condenser 6, the former being shown as a portion of said conduit that is inclined downwardly toward the generator-absorber, and the latter as a coiled portion of said conduit. Both the dehydrator and condenser are located within a box or casting 7, shown as equipped with a filling cap 8, and adapted to permanently contain, preferably to its full capacity, a cooling agent, such as water.

In each of the embodiments, the delivery conduit leads downwardly through the top of the evaporator to a point near the bottom thereof so that as long as practically any liquid is present in the evaporator it will seal said conduit against the escape of ammonia gas from the evaporator therethrough. The advantage of this arrangement will be pointed out presently. In every case the bottom of the evaporator is desirably formed to provide a sump or basin into which the discharge end of the delivery conduit dips, and wherein the residue liquid in the evaporator collects by gravity. While the curved bottom wall of a spherical or horizontally disposed cylindrical vessel, or any equivalent thereof, would, to a large measure serve the purpose, I show, in Figs. 1, 2 and 4, a sump designated 2^a in the form of a distinct depression in the bottom wall of the evaporator. For claim purposes this sump or basin will, in some instances be referred to as a receiver.

The generator-absorber is preferably equipped with heat abstracting veins 10, similar in style and purpose to the fins on the cylinder of an air-cooled motor, and this vessel is shown as located in a vertical flue, indicated by dot-and-dash lines and designated 11. The evaporator is placed in the refrigeration compartment, also indicated by dot-and-dash lines and designated 12.

In the broader aspect of the invention the generator-absorber unit of the apparatus may, in accordance with prior practice, comprise separate chambers or vessels wherein the respective processes of generation and absorption are carried on and likewise the evaporator-receiver may consist of different compartments or containers in the former of which the refrigerant condensate is collected and from the latter of which it evaporates. Where used herein, the terms "generator-absorber", "generator-absorber section", "generator-absorber end of the system", "evaporator", "evaporator-receiver", "evaporator section" and "evaporator end of the system", are to be understood as embracing all modifications of the respective elements.

Situated below the generator-absorber is an oil burner 15, preferably of the so-called wickless type, that receives its supply of fuel through a pipe 16 from a cup 17 within which is adapted to be placed in inverted position a font or reservoir 18 which, in the present case, is in the form of a bottle. This font or reservoir is of sufficient capacity to accommodate just enough oil to supply heat for initiating one cycle of operation of the apparatus and, for convenience, the user may be supplied with a number of such reservoirs so that to replenish the fuel supply for each operation means simply the removal of an empty font or reservoir and the substitution therefor of a full one.

Associated with each embodiment of the invention is a liquid return means or siphon that is designated generally by the reference numeral 20, the same being altered in proportions to suit the various structures. It is this siphon that constitutes the means for returning to the generator-absorber any residue liquid left in the evaporator end of the system after each cooling period. The action of the liquid return means or siphon will be fully explained hereinafter.

Referring now to the form of the invention illustrated in Fig. 1, the evaporator 2 is surmounted by a gas dome 25, downwardly through the top wall of which extends the adjacent end of the discharge conduit 3, said end terminating within the sump 2^a at the bottom of the evaporator. The short leg of the siphon 20 is also extended through the upper portion of the gas dome 25 and has its receiving end disposed within the sump 2^a, while the long leg of the siphon is shown as entering the delivery conduit 3 in substantially the horizontal plane of the upper portion of the gas dome and as descending through said conduit and depending a suitable distance into the generator-absorber. It is to be understood, however, that, so far as the operation of the device is concerned, the long leg of the siphon need not enter the delivery conduit, but may be connected directly to the generator-absorber. The return

conduit 4 connects at one end with the upper portion of the gas dome 25 and its opposite end is extended downwardly through the top wall of the generator-absorber and terminates within this vessel below the minimum liquid level therein which level is indicated by the dotted line *a*. A sleeve 27, which may be common to all forms of the invention, surrounds the discharge end of the return conduit and is suitably supported within the generator-absorber with its lower end spaced from the bottom wall of said vessel. The purpose of this sleeve will be explained when describing the operation of the apparatus.

The system is hermetically sealed and contains a quantity of aqua ammonia or other equivalent refrigerant liquor, and when all the liquor is present in the generator-absorber 1 it stands at about the level indicated by the dotted line *b*. To start the apparatus in operation a reservoir or font 18, filled with oil, is inverted within the cup 17 and the burner 15 is lighted. According to the graph of Fig. 5, whereon is indicated by means of appropriately designated curves, the temperatures and pressure prevailing during a cycle of operation, this act of lighting the burner and thus initiating the cycle is shown as having been performed at 9 o'clock in the morning. By the heat from the burner flame, the temperature of the generator-absorber is raised during the first hour to substantially 325° F., according to the present example. This hour represents the heating period, or the interval of active heat, the fuel supply being such, as hereinbefore stated, as will be exhausted in practically that length of time. During this hour, as indicated by the chart, the pressure within the system rises to substantially 160 pounds, the most abrupt rise occurring within the very early stages of the heating period. On the cessation of heat—that is, after the fuel supply has been exhausted—the temperature of the generator-absorber and the pressure in the system immediately start to drop, as will appear from an inspection of the graph. During the heating period, the ammonia in the generator-absorber is driven out of solution and in the form of vapor rises through the delivery conduit 3 and while passing through the portion of said conduit that constitutes the dehydrator designated by the reference numeral 5 all or the greater percentage of the water vapors wherewith the ammonia gas is saturated condenses and flows back into the generator-absorber, the ammonia gas continuing on through the portion of the conduit that constitutes the condenser 6 and condenses therein, the resultant liquid anhydrous ammonia being discharged into the evaporator 2.

At the conclusion of this phase of the operation the evaporator contains its maximum amount of liquid, the level of which is indicated by the dotted line *c*, and this body of

liquid may contain a relatively small amount of aqueous condensate, it being practically impossible to obtain a complete dehydration of the ammonia vapors.

The cooling period starts with the cessation of heat, or, according to the graph, at the beginning of the second hour, and it continues on until the next heating period which is represented by the graph as twenty-three hours distant. As previously stated, very soon after the heat is removed from the generator-absorber, the pressure within the system starts to drop abruptly. Under these conditions, the liquid ammonia in the evaporator starts to vaporize under the influence of the relatively warm surrounding air in the refrigeration compartment 12, and under the low pressure now prevailing in the system, the water in the generator-absorber attracts the ammonia gas through the return conduit 4. The passage of the gas from the evaporator to the generator-absorber through the return conduit is assured by the fact that the discharge end of the delivery conduit 3 is sealed by the liquid ammonia in the evaporator, and this seal remains effective until the liquid level falls below the end of the conduit 3. This seal which, as will be gathered from the foregoing, prevents the escape of gas from the evaporator through the delivery conduit by way of the condenser and dehydrator to the generator-absorber is rendered especially effective by the fact that a considerable portion of the delivery conduit adjacent its discharge end is housed within the evaporator and thus not only protected from the influence of the relatively warm air within the refrigeration compartment but is maintained cool by the evaporation of the ammonia immediately surrounding it within the evaporator. It will be readily understood that if this portion of the delivery conduit were exposed to the warmer surrounding air, the liquid anhydrous ammonia which it contains would immediately flash into gas and would set up a flow through the delivery conduit contrary to that desired.

As the ammonia gas escapes from the discharge end of the return conduit it is instantly absorbed by the solution in the generator-absorber. This enriches the solution in the immediate vicinity of said end and this enriched or relatively strong liquor, having less specific gravity than the weaker liquor due to its ammonia content, tends to rise within the sleeve 27, thus creating an upward flow of liquid through said sleeve, and this circulation continues as long as ammonia gas is being supplied from the evaporator, thereby insuring a very thorough mixing of the constituents of the aqueous refrigerant.

By the use of the sleeve 27 a very shallow submergence of the return conduit in the liquid in the generator-absorber is permitted

while at the same time high mixing efficiency is attained. Because of the small head of liquid thus maintained in the outlet end of the return conduit, the gas pressure in said conduit and in the evaporator, which has a definite proportion to said head, is considerably less than it would otherwise have to be, and this, in turn, creates within the discharge end of the delivery conduit a correspondingly low level of the liquid anhydrous ammonia. The advantage of this is that said liquid ammonia, standing so low in the portion of the delivery conduit that is housed in the evaporator, is effectively protected from the relatively warm air surrounding the evaporator and is not to any degree gasified and thus inflated so as to cause it to bubble up into the exposed portion of the conduit but said ammonia is maintained in a heavy, dense liquid condition which greatly enhances the seal.

During the evaporation of the liquid anhydrous ammonia and the consequential absorption of heat thereby from the surrounding air in the refrigeration compartment 12, the temperature of said compartment is accordingly lowered and, as indicated by the appropriately designated line on the graph of Fig. 5, this temperature is maintained within a range of less than 10° during the entire cycle of operation, it being the highest at the conclusion of the heating period and the lowest about midway between successive heating periods.

During the early stages of the heating period, when the pressure within the system rises the fastest, a part of any liquid that is present within the evaporator 2 is forced up the short leg of the siphon 20, and a part of the solution in the generator-absorber which at this time has a level of about that indicated by the dotted line b_1 , is likewise forced up the long leg, the quantities of liquid within the two legs approaching each other or meeting within the horizontal branch of the siphon. Any refrigerant gas present within said branch will be absorbed by the liquid and, by reason of such absorption, will attract the separated columns of liquid tending to create a continuous liquid body from one end of the siphon to the other. As soon as this condition prevails a siphonic action is set up in the direction of the generator-absorber which draws all residue liquid then in the evaporator over into the generator absorber, the action being interrupted by the descent of the liquid level in the evaporator below the inlet end of the siphon. This siphonic action occurs during the period so indicated on the graph of Fig. 5. As soon as the siphon has cleared the evaporator of all mixture of absorbent and refrigerant, the performance will not be repeated until the subsequent rise of pressure incident to the

next heating period, and then only in case there is residue liquid in the evaporator.

It may be explained at this point that before the inauguration of the heating period the pressure throughout the system, including that within the siphon 20, is practically uniform. As soon, however, as heat is applied to the generator absorber, the gas pressure within that vessel rises rapidly, as previously set forth, and the same is almost instantaneously communicated, with inconsequential variations, to all other parts of the system, including the interior of the siphon 20 through the intervention of the liquid that is present in and about the legs of the siphon. That is to say: as the pressure rises it tends to equalize throughout the system and as a result thereof it forces the aqua ammonia that is in and about the ends of the siphon tube up into the legs of the siphon and the gas that is trapped between the separated bodies of liquid is compressed to a pressure value substantially equal to that prevailing in the remainder of the apparatus. This gas, in its compressed state, and which is ammonia vapor, is readily absorbed by the aqua ammonia in the ends of the siphon and by reason thereof tends to draw the separated bodies of liquid together. Under this and other influences hereinbefore pointed out the liquid assumes or approaches a state of continuity throughout the length of the siphon with the result that the siphonic action is instituted.

The reasons for the failure of the siphonic action to reoccur at different stages in the operation of the apparatus may be explained as follows: Since more than 75% of the maximum pressure value is attained during about the first 20% (or the first twelve minutes) of the (one-hour) heating period, there will be only a comparatively slight additional rise in pressure while the temperature continues to climb to its maximum in the remaining 80% (or 48 minutes) of the heating period. Within the time of the rapid rise in pressure, there will be practically no ammonia condensate collect in the evaporator because, at the temperatures prevailing, the pressure in the system is yet insufficiently high to promote condensation, the condensation occurring in the interval of slowly rising pressure and, because the additional rise in pressure is slight, the liquid will not be elevated within the legs of the siphon sufficiently to establish a substantially uninterrupted body of liquid throughout the length of the siphon. It may also be pointed out in this connection that at the time of initial heating the pressure of the ammonia gas that is trapped within the siphon by the liquid seals at both ends thereof is low as compared to the rapidly rising pressure in the remaining portions of the system, while at the time we are now considering the pressure within the siphon is substantially the same as that prevailing

through the system. Furthermore, after that time during which the pressure was rising the most rapidly, practically only unadulterated anhydrous ammonia collects in the evaporator, and this will not siphon for the reason that it flashes into gas as soon as it reaches the relatively warm zone where the siphon tube leaves the evaporator. Again, (with respect to the particular embodiments herein illustrated) at a point relatively early in the heating period, and after the siphonic action has taken place, the liquid in the generator-absorber will have boiled away to such an extent as to lower the liquid level in said vessel below the long leg of the siphon, and this condition will positively prevent the setting up of any siphonic action. Thus it will be seen that there is no danger of depriving the evaporator of any of its liquid anhydrous ammonia during the cooling period.

It may be desirable and advantageous, in some installations or embodiments of the invention, due to the cabinet design or the size and shape of the space wherein the apparatus is to be accommodated, to locate the generator-absorber at a higher elevation with respect to the evaporator than it occupies in the arrangement illustrated in Fig. 1. In such a case the inlet end of the siphon must be raised approximately a like distance to the elevation of the generator-absorber as otherwise the two ends of the siphon might be so disposed in relation to each other as to nullify or reverse the siphonic action. Means compensating for such a rearrangement of parts are incorporated in the modifications of the invention illustrated in Figs. 2 and 3.

In Fig. 2 a closed casing 30 replaces the gas dome 25 of the previously described embodiment, and a transfer tube 31 rises from the sump 2^a through the top of the evaporator 2 into the casing 30 and terminates near the top thereof. The siphon 20 is arranged the same in this as in the former embodiment, its shorter leg passing through the upper end of the casing 30 and terminating adjacent the bottom thereof.

The operation of the present embodiment is substantially the same as that above described. During the early stages of the heating period, when the pressure is rising rapidly within the system, any liquid that is left in the evaporator after the cooling period will be forced up the transfer tube 31 into the casing 30 and from said casing, due to the rising pressure therein, up the short leg of the siphon, a corresponding action occurring in the long leg of the siphon, the action continuing in the manner already described until liquid fills the siphon when the siphonic action begins and draws over into the generator-absorber practically all liquid elevated into the casing 30 through the transfer tube 31. The remainder of the

cycle of operation is the same as described above in connection with the first form of the invention.

Fig. 3 illustrates a construction wherein the generator-absorber 1 occupies substantially the same relation to the evaporator 2, as in the above described modification, and this relation of the two vessels is permitted by reason of the fact that a third vessel 35, 10 which serves the same purpose as the casing 30 of the modification shown in Fig. 2, is located a distance above the evaporator. The operation here is the same as that immediately above described. In this case, as with 15 its predecessors, the discharge end of the delivery conduit dips into the liquid anhydrous refrigerant in the evaporator, and a liquid seal is thus effected which prevents the return of the ammonia gas through the 20 delivery conduit.

The modification of the invention illustrated in Fig. 4 differs from the forms previously described principally in the provision of a permanent liquid seal for the end 25 of the siphon 20 that is located in the generator-absorber end of the system. This liquid seal is provided by a cup 38 that is suitably supported within an enlarged portion 39 of the delivery conduit 3 where the 30 latter joins the generator-absorber 1.

After the apparatus is once set in operation, liquid is always present in the cup 38 to a height above the adjacent end of the siphon, and the quantity of liquid in the cup 35 is augmented during each heating period by condensate returning from the dehydrator 5. As in the former cases, the siphonic action occurs in the early stages of the heating period when the pressure is rising rapidly 40 within the system with the result that the liquid surrounding the opposite ends of the siphon is forced up the legs thereof and is attracted by the trapped gas in the horizontal branch of the siphon which is readily 45 absorbed by the liquid, thus establishing a continuous body of liquid throughout the length of the siphon which gravitates through the long leg into the cup 38 and overflows into the generator-absorber. When 50 once the siphonic action is broken the relatively high pressure in the system is communicated to the siphon and is maintained therein upon an accumulation of liquid anhydrous ammonia within the evaporator 55 even after the pressure in the remainder of the system starts to decline. Thus it will be seen that by this arrangement wherein both ends of the siphon are liquid sealed during the cooling period, there is a positive safe-guard against the setting up of 60 any siphonic action during this phase of the cycle of operation.

Reference has been made to the flue 11 within which the generator absorber is situated. The purpose of this flue is two-fold.

While the burner 15 is in operation, it serves to concentrate the heat from the burner on the generator-absorber, and during the cooling period it serves to create a draft of cool air upwardly about the generator-absorber and more rapidly lower the temperature of this vessel so as to promote absorption of the ammonia gas by the weak liquor in the generator-absorber. Some of the heat that is stored within the cooling medium or water 75 in the box or casing 7 is radiated into the upper portion of the flue 11, and this heat rises and contributes to the maintenance of an upward draft of cool air through the lower portion of the flue. It may also be 80 explained that this same action draws cool air between the bottom of the box or casing 7 and the top of the refrigeration compartment, which, with the cool air rising through the flue 11, tend to reduce the temperature of 85 the contents of said box or casing.

It is evident from the foregoing description that at the beginning of each operation, any liquid that is present in the evaporator is automatically drawn over into the generator-absorber. In other words, upon the initiation of each operation, the system is reconditioned for the refrigeration phase of the cycle. On account of this, no preliminaries are necessary to place the apparatus in condition for its first firing after the machine has been assembled, filled and delivered to the user. This relieves the manufacturer of any care in the charging of the system as to the segregation of the liquid therein, and the user 90 of having to give any attention to the draining of the contents into the generator-absorber preparatory to starting the apparatus in operation.

Having thus described my invention, what 95 I claim is:

1. In refrigeration apparatus of the intermittent absorption type consisting of a closed system involving a generator-absorber section, and evaporator section and vapor conveying means through which said sections communicate; and a siphon independent of said means having its short leg opening into the evaporator section and its long leg opening into the generator-absorber section, the 100 siphon being otherwise closed throughout its length to the interior of the system.

2. In refrigeration apparatus of the intermittent absorption type consisting of a closed system, in combination with the generator-absorber unit and the evaporator unit, fluid conveying means through which said units communicate, a siphon independent of said means and having its short leg opening into the evaporator unit and its long leg opening into the generator-absorber unit, the siphon being otherwise closed throughout its length to the interior of the system, and a receiver 105 in which one terminal of the siphon is disposed.

3. Refrigeration apparatus of the intermittent absorption type consisting of a closed system and involving a generator-absorber and an evaporator, a gas dome rising from the evaporator, a delivery conduit leading from the generator-absorber through the top of said dome and downwardly through the evaporator and terminating adjacent the bottom thereof whereby liquid in the evaporator forms a seal for the discharge end of said conduit, a return conduit leading from said gas dome to the generator-absorber and terminating in the latter vessel below the minimum liquid level therein, and a siphon having its short leg extended downwardly through the upper portion of the gas dome and terminating adjacent the bottom of the evaporator and having its long leg extending downwardly through the end of the delivery conduit adjacent the generator-absorber, the latter end of said siphon being adapted to be liquid sealed in the generator-absorber end of the system.
4. In refrigeration apparatus of the intermittent absorption type consisting of a closed system, in combination with the generator-absorber section and the evaporator section of said system, a dehydrator for the vapors that pass from the generator absorber section, a receptacle disposed within the generator-absorber section and into which said dehydrator discharges, and a siphon having its short leg terminating in the evaporator section and its long leg terminating in said receptacle.
5. A refrigerator of the intermittent absorption type consisting of a closed system comprising a generator-absorber, an evaporator, a delivery conduit leading from the generator-absorber to the evaporator and involving a condenser, a return conduit leading from the evaporator to the generator-absorber, the system enclosing a refrigerant and an absorbent for the refrigerant, means for intermittently heating the generator-absorber, means for cooling the generator-absorber during the intervals between heating periods, and a siphon having its short leg terminating in the evaporator and its long leg terminating in the generator-absorber.
6. A refrigerator of the intermittent absorption type consisting of a closed system comprising a generator-absorber, an evaporator, a delivery conduit leading from the generator-absorber to the evaporator and involving a condenser, a return conduit leading from the evaporator to the generator-absorber, the system enclosing a refrigerant and an absorbent for the refrigerant, means for intermittently heating the generator-absorber, means for cooling the generator-absorber during the intervals between heating periods, and a siphon having its short leg terminating near the bottom of the evaporator and its long leg terminating in the genera-
- tor-absorber and adapted to be liquid sealed therein.
7. A refrigerator of the intermittent absorption type consisting of a closed system comprising a generator-absorber, an evaporator, a delivery conduit leading from the generator-absorber to the evaporator and involving a condenser, a return conduit leading from the evaporator to the generator-absorber, the system enclosing a refrigerant and an absorbent for the refrigerant, means for intermittently heating the generator-absorber, means for cooling the generator-absorber during the intervals between heating periods, a receiver in which the residue liquid left in the evaporator is collected at the conclusion of the cooling period, and a siphon for transferring liquid from said receiver to the generator-absorber, the siphon being initially filled due to changes in pressure in the system.
8. A refrigerator of the intermittent absorption type consisting of a closed system comprising a generator-absorber, an evaporator, a delivery conduit leading from the generator-absorber to the evaporator and involving a condenser, a return conduit leading from the evaporator to the generator-absorber, the system enclosing a refrigerant and an absorbent for the refrigerant, means for intermittently heating the generator-absorber, means for cooling the generator-absorber during the intervals between heating periods, the bottom of the evaporator being formed to provide a sump, and a siphon having its short leg terminating in the sump and its long leg terminating in the generator-absorber.
9. The combination with refrigeration apparatus of the intermittent absorption type involving a generator-absorber and an evaporator-receiver, the latter being located at an elevation above the maximum liquid level in the generator-absorber, and communicative means through which a complete operative refrigeration cycle is effected; of a liquid return conduit independent of the beforementioned communicative means connecting the evaporator-receiver with the generator-absorber, a portion of which conduit is at an elevation above the maximum liquid level in the evaporator-receiver.
10. The combination with refrigeration apparatus of the intermittent absorption type involving a generator-absorber and an evaporator-receiver, the latter being located at an elevation above the maximum liquid level in the generator-absorber, and communicative means through which a complete operative refrigeration cycle is effected; of a valveless liquid return conduit independent of the beforementioned communicative means connecting the evaporator-receiver with the generator-absorber.
11. The combination with refrigeration apparatus of the intermittent absorption type

involving a generator-absorber with means for heating and cooling the same and an evaporator-receiver, the latter being located at an elevation above the maximum liquid 5 level in the generator-absorber, and communicative means through which a complete operative refrigeration cycle is effected; of a conduit independent of the beforementioned communicative means that opens into the 10 evaporator-receiver and the generator-absorber and is otherwise closed to the remainder of the system and has a part above the maximum liquid level in the evaporator-receiver, said conduit being liquid sealed in the 15 generator-absorber at the beginning of the heating periods.

12. The combination with refrigeration apparatus of the intermittent absorption type wherein a refrigerant fluid and an absorbent 20 fluid are used, and involving a generator-absorber section, with means for alternately heating and cooling the same, and an evaporator section, and communicative means for conveying refrigerant fluid between the 25 sections and which means is necessary to a complete operative refrigeration cycle; of a conduit independent of said communicative means for transferring absorbent fluid remaining in the evaporator section at the end 30 of each cooling period to the generator-absorber section at the beginning of the following heating period, said conduit having its receiving end opening into the residue liquid collecting portion of the evaporator section 35 and its discharging end liquid sealed in the generator-absorber section at the beginning of the heating periods, the intermediate portion of said conduit being at an elevation above the maximum liquid level in the evaporator section. 40

13. The combination with refrigeration apparatus of the intermittent absorption type wherein a refrigerant fluid and an absorbent fluid are used, and involving a generator-absorber 45 section, with means for alternately heating and cooling the same, and an evaporator section, communicative means for conveying refrigerant fluid between the sections and which means is necessary to a complete operative refrigeration cycle, and means for liquefying fluid delivered to the evaporator section; of a conduit independent of said communicative means for transferring absorbent liquid remaining in the evaporator section at 50 the end of each cooling period to the generator absorber section at the beginning of the following heating period, said conduit having its receiving end opening into the residue liquid collecting portion of the evaporator section 55 and its opposite end liquid sealed in the generator-absorber section at the beginning of the heating periods, said conduit being out of communication with the liquefying means excepting through the evaporator section and having its intermediate portion at 60

an elevation above the maximum liquid level in the evaporator section.

14. The combination with refrigeration apparatus of the intermittent absorption type 70 involving a generator-absorber containing refrigerant liquid and absorbent liquid, and an evaporator-receiver that is located above the plane of maximum liquid level in the generator-absorber, means for alternately heating and cooling the generator-absorber, and communicative means between the generator-absorber and the evaporator-receiver necessary to a complete operative refrigeration cycle as the same is effected by an alternate heating and cooling of the generator-absorber; of a conduit independent of said communicative means for automatically returning any absorbent liquid remaining in the evaporator-receiver at the end of a cooling period from said evaporator-receiver to the generator-absorber during the early stages of the next heating period, such returning of the liquid being initiated by a rise in pressure in the system when the generator-absorber is heated. 80

15. The combination with refrigeration apparatus of the intermittent absorption type wherein a refrigerant fluid and an absorbent fluid are used, and comprising a closed system involving a generator-absorber section, an evaporator section, and communicative means for conveying refrigerant fluid between the sections in the attainment of a complete operative refrigeration cycle, together with means for intermittently supplying heat to the generator-absorber section; of a conduit for recovering absorbent fluid carried over into the evaporator section and returning it to the generator-absorber section, the flow of absorbent fluid through said conduit being initiated by a change in pressure in the system, said conduit being capable of receiving refrigerant fluid from the evaporator section and being in part exposed to a temperature sufficiently high to vaporize or maintain in vaporized condition any refrigerant fluid gaining access to the part of the said conduit so exposed whereby, upon the passage of refrigerant fluid through said conduit, the same will be vaporized and interrupt the flow of liquid through the conduit. 90

16. The combination with refrigeration apparatus of the intermittent absorption type wherein a refrigerant fluid and an absorbent fluid are used, and involving a generator-absorber section, an evaporator section, and communicative means for conveying refrigerant fluid between the sections in the attainment of a complete operative refrigeration cycle, and means for intermittently supplying heat to the generator-absorber section; of a conduit for returning to the generator-absorber section liquid in the evaporator section at the beginning of 100 110 115 120 125 130

the heating period, a part of said conduit being so situated as to cause it to reach a sufficiently high temperature after the beginning of the heating period to vaporize liquid refrigerant entering said part of the conduit thereby to interrupt the flow of liquid through the conduit and prevent the return of liquid thereafter.

17. The combination with refrigeration apparatus of the intermittent absorption type wherein a refrigerant fluid and an absorbent fluid are used, and comprising a closed system involving a generator-absorber section, an evaporator section, and communicative means for conveying refrigerant fluid between the sections in the attainment of a complete operative refrigeration cycle, together with condenser means and means for intermittently supplying heat to the generator-absorber section, the portion of each cycle during which the heat supplying means is effective being known as the heating period the latter part of which constitutes a condensing phase; of a conduit for returning to the generator-absorber section liquid in the evaporator section at the beginning of each heating period, a part of said conduit being so situated as to cause it to reach a sufficiently high temperature during the condensing phase to vaporize liquid refrigerant entering said part of the conduit thereby to interrupt the flow of liquid through the conduit and prevent the return of liquid thereafter.
18. The combination with refrigeration apparatus of the intermittent absorption type wherein a refrigerant fluid and an absorbent fluid are used, and comprising a closed system involving a generator-absorber section, an evaporator section, and communicative means for conveying refrigerant fluid between the sections in the attainment of a complete operative refrigeration cycle, together with means for intermittently supplying heat to the generator-absorber section, the portion of each cycle during which the heat supplying means is effective being known as the heating period; of a conduit for returning to the generator-absorber section liquid in the evaporator section at the beginning of the heating period, a part of said conduit being situated in heat exchanging relation to the aforesaid communicative means so that said part of the conduit will reach a sufficiently high temperature during the early phase of the heating period to vaporize liquid refrigerant entering said part of the conduit thereby to interrupt the flow of liquid through the conduit and prevent the return of liquid thereafter.

In testimony whereof, I hereunto affix my signature.

DAVID F. KEITH.
